UNITED STATES PATENT OFFICE.

AXEL G. J. RAPP, OF CHICAGO, ILLINOIS, ASSIGNOR TO LINK-BELT COMPANY, OF CHICAGO, ILLINOIS, A CORPORATION OF ILLINOIS.

CASTING-HANDLING MACHINE.

Application filed January 11, 1923. Serial No. 611,988.

To all whom it may concern:

Be it known that I, AXEL G. J. RAPP, a citizen of the United States, residing at Chicago, in the county of Cook and State of Illinois, have invented a certain new and useful Improvement in Casting-Handling Machines, of which the following is a specification.

This invention relates to a moving table which is intended primarily for the handling of castings, and is designed particularly as a means for removing the sand cores from the castings and for collecting the sand. One object is to provide in a machine of the type suggested an apparatus which will permit of very great capacity wherein a large number of castings may be rapidly cleaned and which will occupy a limited space. Another object is to provide a means which will readily recover and collect the greatest possible proportion of the sand. Other objects will appear from time to time throughout the specification and claims.

My invention is more or less diagrammatically illustrated in the accompanying drawings, wherein:

Figure 1 is a plan view of one form of the apparatus;

Figure 2 is a vertical cross section on an enlarged scale taken on the line 2—2 of Figure 1;

Figure 3 is a partial cross section on an enlarged scale taken on line 3—3 of Figure 1 showing particularly the table supporting means;

Figure 4 is a partial cross section taken on line 4—4 of Figure 1 showing one form of the driving means.

Like parts are designated by like characters throughout.

The table is preferably circular and is mounted for rotation. The table consists of an inner band A and an outer peripheral band A¹. Each of these bands has on its inner face a grate supporting angle B B. The inner bands are joined by attaching means C. Projecting vertically downward from the inner band A are a plurality of members D to which may be secured gusset plates D¹. Projecting inwardly and downwardly from the outer member A¹ are a plurality of bracing members E. These members may have additional supporting gusset plates E¹, and extend downward toward the downward end of the members D.

Beneath the upper surface of the table and parallel to it and attached to the members D and E are supporting members F.

Supported upon the members F, fastened to the inner angles B and supported by the gusset plates D¹ is an irregularly bent hopper bottom and side member G having an inclined side portion and a generally horizontal bottom portion. In opposition to this member and attached to the outer band A¹ and to the gusset plates E¹ is a hopper side member G¹ which extends inwardly and downwardly toward the member G but leaves an opening G² through which sand may be discharged from the hopper.

About the inner edge of the table is mounted an angle H. Below this is a second angle H¹ which has secured to its under face an inverted rail H².

At suitable intervals about the interior of the table are mounted supporting members I which carry bearings I¹. From these bearings, upon axles I² are supported a plurality of wheels I³. The rails H² rest upon and are supported by these wheels.

Mounted at the bottom of the table on its inner side is an annular rack J. Meshing with this rack is a pinion J¹ carried by a shaft J² which is driven by a motor J³ through a reducing gear J⁴. This driving mechanism is not shown in great detail as it forms no part of the invention.

Extending substantially about the table and lying adjacent to the horizontal portion of the hopper member G is a skirt or screen K which serves as a safety guard member for the workman and those working about the machine to prevent injuring them.

L is a conveyor, here shown as an endless belt conveyor, although another form of conveyor might be substituted. This conveyor extends under the table and runs about a roller L¹. Discharging upon the conveyor is a chute L². Material is directed into the chute from the hopper by means of the plow L³. This plow extends diagonally across the horizontal portion of the part G of the hopper, and as the table moves the sand is directed by the plow into the hopper and so into the conveyor.

Resting in the angles B B are a plurality of removable grid sections. These sections are formed of a number of longitudinal rods M M upon which are mounted a plurality of bars M'.

Although I have shown an operative device, still it will be obvious that many changes in size, shape and arrangement of parts might be made without departing materially from the spirit of my invention, and I wish therefore that my showing be taken as in a sense diagrammatic.

The use and operation of my invention are as follows:

10 The castings as they are formed are placed upon the grills on the top of the table either by hand or by any simple mechanical conveyor. As the table rotates the sand cores are removed from the castings. They may 15 be driven out by hand or removed in any suitable fashion. The sand as it falls from the castings falls through the grills and down into the annular hopper. As the table carrying the hopper with it moves, the 20 plow extends into the path of the sand and thus scrapes it from the horizontal portion of the hopper member and directs it into the chute. From the chute it falls into the conveyor, and is thus removed.

25 I claim:

1. In combination in a casting handling machine an annular table adapted to support castings and provided with passages therethrough to permit material from the 30 castings to pass downward mounted for rotary movement, an annular hopper beneath said table fastened thereto, there being an extended open space inside of said table substantially free from obstructions.

35 2. In combination in a casting handling machine an annular table adapted to support castings and provided with passages therethrough to permit material from the castings to pass downward mounted for 40 rotary movement, and an annular hopper beneath said table and attached thereto, a laterally extending plate beneath said hopper attached thereto of such width normally to prevent discharge from said hopper.

45 3. In combination in a casting handling machine an annular table adapted to support castings and provided with passages therethrough to permit material from the castings to pass downward mounted for 50 rotary movement, and an annular hopper beneath said table and attached thereto, having a discharge passage at the bottom thereof, a laterally extending plate beneath said hopper attached thereto of such width normally to prevent discharge from said hopper, and a plough held stationary and 55 extending over said plate and adapted to remove material therefrom.

60 4. In combination in a casting handling machine an annular table adapted to support castings and provided with passages therethrough to permit material from the castings to pass downward mounted for 65 rotary movement, and an annular hopper beneath said table and attached thereto

having a discharge passage at the bottom thereof, a laterally extending plate beneath said hopper attached thereto, of such width normally to prevent discharge from said hopper, and a plough held stationary and 70 extending over said plate and adapted to remove material therefrom, in combination with a conveyor adapted to receive material transmitted thereto by said plough.

5. In combination in a casting handling 75 machine an annular table adapted to support castings and provided with passages therethrough to permit material from the castings to pass downward mounted for rotary movement, and an annular hopper 80 beneath said table and attached thereto having a discharge passage at the bottom thereof, a laterally extending plate beneath said hopper attached thereto of such width normally to prevent discharge from said 85 hopper, and a stationary wall surrounding said plate and adjacent the edge thereof adapted to prevent accidental spilling of material therefrom.

6. In combination in a casting handling 90 machine an annular table adapted to support castings and provided with passages therethrough to permit material from the castings to pass downward mounted for rotary movement, and an annular hopper 95 beneath said table and attached thereto having a discharge passage at the bottom thereof, a laterally extending plate beneath said hopper attached thereto of such width normally to prevent discharge from said 100 hopper, and a plough held stationary and extending over said plate and adapted to remove material therefrom, and a stationary wall surrounding said plate and adjacent the edge thereof adapted to prevent accidental spilling of material therefrom.

7. In combination in a casting handling machine an annular table adapted to support castings and provided with passages therethrough to permit material from the castings to pass downward mounted for rotary movement, and an annular hopper beneath said table and attached thereto having a discharge passage at the bottom thereof, a laterally extending plate beneath said hopper attached thereto of such width normally to prevent discharge from said 110 hopper, and a plough held stationary and extending over said plate and adapted to remove material therefrom, in combination with a conveyor adapted to receive material transmitted thereto by said plough, there 115 being an extended open space inside said table substantially free from obstruction.

8. In combination in a casting handling 125 machine an annular table adapted to support castings and provided with passages therethrough to permit material from the castings to pass downward mounted for rotary movement, and an annular hopper 130

beneath said table and attached thereto having a discharge passage at the bottom thereof, a laterally extending plate beneath said hopper attached thereto of such width 5 normally to prevent discharge from said hopper, and a plough held stationary and extending over said plate and adapted to remove material therefrom, and a stationary wall surrounding said plate and adjacent the edge thereof adapted to prevent accidental spilling of material therefrom, there being an extended open space inside said table substantially free from obstruction.

Signed at Chicago, county of Cook and State of Illinois, this 8th day of January, 15 1923.

AXEL G. J. RAPP.
